DESIGN FOR A HOLDER FOR INKWELLS AND PENS

William M. Gallagher, Oklahoma City, Okla.

Application May 5, 1942, Serial No. 106,801

Term of patent 14 years

To all whom it may concern:

Be it known that I, William M. Gallagher, a citizen of the United States and a resident of Oklahoma City, in the county of Oklahoma and State of Oklahoma, have invented a new, original, and ornamental Design for a Holder for Inkwells and Pens, of which the following is a specification.

Reference is had to the accompanying drawing, forming part thereof, in which:

I claim:

The ornamental design for a holder for inkwells and pens, as shown.

WILLIAM M. GALLAGHER.
